UNITED STATES PATENT OFFICE.

HARRY M. MCINTOSH, OF CHICAGO, ILLINOIS.

VENTILATED HATCH.

SPECIFICATION forming part of Letters Patent No. 650,477, dated May 29, 1900.

Application filed May 18, 1899. Serial No. 717,268. (No model.)

To all whom it may concern:

Be it known that I, HARRY M. MCINTOSH, a citizen of the United States, and a resident of the city of Chicago, in the county of Cook and State of Illinois, have invented certain new and useful Improvements in Ventilated Hatchways, of which the following is a specification.

My invention relates, primarily, to that class of ventilators in which an opening or hatchway in the top or roof of a storage-apartment—such, for instance, as a car-body—is made use of as a passage-way for the ventilating-current. Its objects are to vary the ordinary standards of construction as little as possible, to do away with unnecessary parts, and to provide a simple but strong, durable, and effective hatch or cover for such openings which will at all times protect the contents of the storage-space and yet will afford means for directing the ventilating-current through the same.

For a proper understanding of the invention it will be sufficient to describe it in connection with an ordinary ventilated or refrigerator car.

In the drawings, Figure 1 is a perspective view of a car-body, showing my device attached thereto. Fig. 2 is an enlarged perspective of one of my ventilated hatches on a portion of a car-roof, the remainder being broken away, the hatch proper being closed, but the ventilating device open. Fig. 3 represents the same with the ventilator closed. Fig. 4 shows the hatch, with ventilator closed as shown Fig. 3, thrown open to show the interior construction.

Further referring to the drawings, in which like characters represent like parts throughout, A is the body of a car, and B the roof thereof.

C represents one of the hatchways in the roof, and D the coaming surrounding the same.

E is a hatch or cover constructed in a substantial manner, with the outside timbers or framing *e*, the diagonal timbers *e'*, and such other framework or bracing as may be desirable to furnish a solid and rigid structure.

All that portion of the hatch not embraced between the timbers *e' e'* is covered with the decking *e''*, the whole forming a solid and sub-

stantial construction, which is hinged to the hinge-cleat *F* by the hinges *f*. The V-shaped or triangular space between the timbers *e' e'* is covered or protected by a screen *G* of sufficiently-small mesh to keep out cinders and the like, and as a support for the same and as a protection against entry to the car through the same space a heavy screen of coarser mesh or metal bars *g* may be provided underneath the screen *G*. A hasp *H*, staple *h*, and sealing-hook *h'* or other suitable means for fastening the hatch in the closed position are shown.

Within the aforesaid V-shaped space formed by the timbers *e' e'* and the decking *e''* laid thereon, and which trends lengthwise of the car or in the direction in which air-currents will be directed, are fitted two fan-shaped lids *I* and *I'*. The bodies of these lids may be of equal or unequal width; but by reason of certain practical advantages in construction and application I prefer to make them unequal, as shown in the drawings. One of the lids—in this case the narrow one *I'*—carries an extension-plate giving an overlap *i* of such dimensions that the width thereof added to that of its lid will approximately equal that of the lid *I*. The latter is provided with a staple-like projection or projections *j*, which pass through corresponding openings in the edge of the plate *i*. A hook and chain furnish means for fastening the lids together in the position shown in Fig. 2 or of securing the same in the closed position to the staple *j*, as shown in Fig. 3.

f' is a small opening in the hinge-cleat *F*, through which cinders and dust which might otherwise lodge on the screen *G* may be blown by the air-currents passing over the same. The rear ends of the lids are or may be truncate the breadth of this opening, as shown, so that when raised into the position shown in Fig. 2 they form, with the screen, a funnel, the spout of which registers with this opening and through which cinders and dust may be forcibly expelled. When the lids are down, however, as in Fig. 3, these truncated ends shut against or slightly into the opening *f'* and close it.

In the use of my ventilated hatch when applied to a refrigerator-car I take advantage of the ordinary ice holes or openings. These

are four in number—two at each end of the car—with their hatches opening away from the end of the car nearest thereto. It has been customary to partially open these hatches or 5 covers, and by securing the same in that position the currents of air caused by the motion of the train have been deflected downwardly and through the car. To protect the interior thereof against intruders at such 10 times, various expedients have been adopted, all involving the use of movable or hinged screens and of supporting-wings and the like. These are all very liable to loss and injury and subject to various practical disadvantages, especially as they are required to support the heavy hatch or cover. My improved 15 ventilated hatch allows the screen or screens to be made stationary as an attachment to the hinged hatch, and when the ventilating 20 device is used the auxiliary lids are simply raised and placed in position, where they have only their own weight to support and not that of a heavy cover in addition to their own.

It will be observed that in my device the 25 operations of the hatch or cover proper and of the ventilating features thereof are separate and distinct from each other, though physically united. As a hatch or protection for the hatchway or opening the device may 30 be used irrespective of whether the ventilating-lids are open or closed, and unless there is special reason for opening the same the hatch may remain closed while the ventilating-lids are adjusted; but when the hatch or 35 cover is opened it lifts the ventilator and screen bodily with it from the hatchway and leaves the latter clear and unobstructed.

When used in any position exposed to rain or drip, the overlapping lid is given sufficient 40 slant to form a watershed. On a sloping roof this slant may be secured by placing the overlapping lid on the higher side. In a refrigerator or other car the hatches are preferably in pairs, so that the extension portion, plate, or 45 wing shall be on the lid on the upper side of the car-roof and overlap the lower lid.

The embodiment of my invention may be varied in many ways from the practical and operative device shown without departing 50 from the spirit or principles thereof. I do not limit myself to the construction shown nor to the application to any particular kind of building, structure, car, or vehicle.

I claim as new and desire to secure by Letters Patent—

1. A hatch or cover for the hatchways of refrigerator-cars and the like, arranged on hinges to open bodily away from the hatchway and having a ventilating-aperture there- 60 in, a protecting-screen for the said aperture mounted in said hatch, lids to close the aperture, and an extension plate or wing on the one lid overlapping the other lid, the said lids being pivotally attached to said hatch 65 and adapted when raised into mutually-inclined positions to form an air - deflecting hood, substantially as described.

2. A hatch or cover for the hatchways of refrigerator-cars and the like, pivotally attached to the roof thereof and having a ventilating-aperture therein, a protecting-screen for said aperture, fan-shaped lids to close the same, and an extension plate or wing on the one lid overlapping the other lid, the said lids being pivotally attached to the hatch on 75 converging axes and adapted when raised to form an air-deflecting hood, substantially as shown and described.

3. A hatch or cover for the hatchways of refrigerator-cars and the like, pivotally attached to the roof thereof to open bodily away from the hatchway and having a ventilating-aperture therein, a protecting-screen for said aperture, fan-shaped lids to close the same, and an extension plate or wing on 85 the one lid overlapping the other lid, the said lids being pivotally attached to the hatch on converging axes and adapted when raised to form an air-deflecting hood, substantially as shown and described.

4. A hatch or cover for the hatchways of refrigerator-cars and the like, pivotally attached to the roof thereof to open bodily away therefrom and having a fan-shaped opening therein, a protecting-screen for the 95 said opening, fan - shaped lids to close the same, and an extension plate or wing on one of said lids to overlap the other lid, the said lids being pivotally attached to the hatch on converging axes and adapted when raised 100 into mutually-inclined positions to form an air-deflecting hood, substantially as shown and described.

5. A hatch or cover for the hatchways of refrigerator-cars and the like, pivotally attached to the roof thereof to open bodily away therefrom and having a fan - shaped ventilating - opening therein, a protecting-screen for the said opening, fan-shaped lids of unequal width to close the same, and an 110 extension plate or wing on the one lid overlapping the other lid, the said lids being pivotally attached to said hatch on converging axes and adapted when raised into mutually-inclined positions to form an air-deflecting 115 hood, substantially as shown and described.

6. In combination with a car having a plurality of openings or hatchways in the roof, a hatch or cover for each opening having a ventilating - aperture therein, said cover including lids pivotally hinged on opposite sides of said aperture on axes converging toward each other and trending lengthwise of the car, and means for securing the said lids together in raised and mutually-inclined positions to form a ventilating-hood.

7. In combination with a car having a plurality of openings or hatchways in the roof thereof, a hatch or cover for each opening pivotally attached to the car-roof to open bodily away therefrom and having a ventilating-aperture therein, a protecting-screen for said aperture, and lids pivotally hinged on opposite sides thereof on converging axes

trending lengthwise of the car, the said lids being adapted when raised to form a ventilating-hood, substantially as shown and described.

- 5 8. In combination with a car having a plurality of openings or hatchways in the roof thereof, a hatch or cover for each opening pivotally attached to the car-roof to open bodily away therefrom and having a ventilating-aperture therein, a protecting-screen for the said aperture, lids to close the same, and an extension plate or wing on the one lid overlapping the other lid, the said lids being pivotally attached to said hatch and adapted 15 when raised into mutually-inclined positions to form an air-deflecting hood.
9. A hatch or cover for an inclined hatchway, hinged along a sloping side of said hatchway to open bodily therefrom and having a 20 triangular ventilating-aperture therein, a protecting-screen for said aperture mounted in said hatch, triangular lids to close the aperture independently hinged to said hatch at the upper and lower sides of said aperture, 25 an extension plate or wing upon the upper lid to overlap the lower lid and form a watershed when closed, and means for locking said lids together, when open, to form an air-deflecting hood, substantially as described.
- 30 10. A hatch or cover for a ventilating-hatchway, comprising a screen over the hatchway,

lids adapted when open to form an air-deflecting hood above said screen, and an opening at the rear of the hood, above said screen, for the escape of dust and cinders, substantially as shown and described. 35

11. A hatch or cover for a ventilating-hatchway, comprising a screen over the hatchway, lids adapted when open to form a funnel-shaped air-deflecting hood above said screen, 40 and an opening coinciding with the apex of said funnel, above the screen, for the escape of dust and cinders, substantially as shown and described.

12. A hinged hatch or cover for a ventilating-hatchway, arranged to open bodily therefrom, and having a triangular ventilating-aperture, a screen covering said aperture, triangular overlapping lids hinged at the sides of the aperture and adapted when raised to 45 form a funnel-shaped hood, and a spoutway at the rear of said lids and above the screen, arranged to be opened by the opening of the said lids, substantially as shown and described. 55

In witness whereof I have set my hand this 4th day of May, 1899.

HARRY M. MCINTOSH.
